UNITED STATES PATENT OFFICE

2,607,050

ERECTOR AND AMBULATOR DEVICE

Willis F. Binschoff, New York, N. Y.

Application November 22, 1949, Serial No. 128,894

1 Claim. (Cl. 5—81)

1

This invention relates to an erector and ambulator device.

It is an object of the present invention to provide a device adapted for the removal of an inert invalid from the bed in order that the patient may be placed in an erect or semi-erect position to alleviate the possibility of bed pneumonia or circulatory complications due to inactivity, the patient being strapped to the device so that the patient will be supported at several locations and will be held erect as the device is turned on end so that the patient's weight can be taken by the foot board which is hinged upwardly and supported and wherein wheels may be applied to the device to permit the transport of the patient outdoors for sunlight or other distant points from the bed.

It is another object of the present invention to provide a device for erecting and moving patients which will cut down on the number of people needed in the hospital to erect and move patients and thereby provide a device for hospitals and convalescent homes for the handling of fractures and paraplegic cases.

Other objects of the present invention are to provide a patient erector and ambulator which is of simple construction, inexpensive to manufacture, convenient to use, has a minimum number of parts, easy to assemble upon the patient, rugged and safe and efficient in operation.

For other objects and for a better understanding of the invention, reference may be had to the following detailed description taken in connection with the accompanying drawing, in which

Fig. 1 is a perspective view of a bed and of the device embodying the features of the present invention with the foot board extended and the head rest assembled upon the device, the device resting upon the bed in readiness to receive the patient.

Fig. 2 is a side elevational view of the device with the parts assembled thereon including the wheels and the device supported at an angle.

Fig. 3 is an enlarged fragmentary view showing the tie rod element which is inserted in the board and connected to a fixture on the foot member in order that the foot member can be held angled with respect to the board.

Fig. 4 is a fragmentary and sectional view of the device and looking upon the wheeled bracket.

Fig. 5 is a perspective view of one of the straps which are connected across the board to support the patient when the board is placed in the upright position and including a fragment of the board to show the manner in which the snap element is connected to the board.

2

Fig. 6 is a perspective view of a foot rest.

Fig. 7 is a perspective view of the head rest.

Fig. 8 is a rear perspective view of the device fully assembled and illustrating the manner in which the device is supported.

Fig. 9 is a sectional view of a fragmentary portion of the handle fastener.

Referring now to the figures, 10 represents a bed having a mattress 11 on which the patient 12 is reclining. With the patient to one side of the bed, the device, as indicated at 13, can be placed upon the bed so that the patient can be rolled onto the same. With the patient on the board, various parts of the same can be assembled to it.

The device 13 includes a main board 14 along each side of which there are arranged groups of holes 15 having pins 16 extending within the same and to which snap elements 17 of a large retaining strap 18 can be attached to hold the patient upon the board 14. These holes also serve as convenient places to grip the board. This strap 18 has tongues 19 at the opposite ends of the same which are slid through the respective snap elements and are secured to buckles 21 and the buckle pin 22. These straps can be extended across the legs, the abdomen and across the shoulders, as indicated by the vertically spaced groups of these openings 15, Fig. 1.

The upper end of the board is provided with openings, as indicated at 23, to adjustably and releasably retain head rest 24. Dowel pins 25 will extend into these holes 23.

A foot board 26 is hinged to the lower end of the board at 27. A semi-fitted arch board 28 is permanently secured to the adjustable foot board 26. This semi-fitted arch board has formed depressions 29, Fig. 6. Once the patient has been placed on the board 14, the foot board 26 is elevated and retained in the elevated position by the insertion of a tie rod 31 in a plate 32 having opening 33 for receiving the rod end. The upper end of the rod has an enlargement 34 thereon and is bent, as indicated at 35, so that the enlargement may enter an opening 36 in the edge of the foot board 26. Fitted over the edge of the foot board 26 is a folded plate 37 of metal with a top opening 38 through which access for the enlargement 34 can be had with the opening 36. This plate is fastened to the foot board by screws 39. The plate also has a drop slot 41 for receiving the rod 31. In order to keep the tie rod fixed within the openings 36 and 38, a latch 42 is slid under the plate and over the enlargement 34 of the tie rod. With the foot board elevated and held in that position, there is provided a

support for the feet of the patient. To keep the patient's feet in alignment, the depressions 29 in the arch board 28 are provided.

When the foot board is lowered to the floor, and the head raised to vertical position, a wheel saddle 44 having wheel 45 can be attached by inserting bolt 46 in hole 48—49 and a wing nut 47 is attached in the manner as shown in Fig. 4. There is one of these wheel saddles placed at each side of the board. There is provided, at the respective sides of the board, holes 48 and 49 for these saddles.

After the straps are extended across the patient, the device can be lowered onto the floor and by gripping the head end of the same it can be elevated to an upright position, as illustrated in Fig. 2, so that the patient can have the feel of being on his feet and yet be thoroughly supported throughout his height. With the foot board on the floor, the board is gently brought upwardly to a vertical position, wheels are attached and handles 57 screwed into threaded plate 58. The device is so stable in the vertical position, that very little effort is required to maintain the same in this position for long periods of time. The number of nurses or help required to erect or move the patient is thus greatly reduced.

To move the patient, the patient is simply tilted back slightly so that the support is upon the wheels and the device and the patient moved along. To support the patient in the inclined position upon the wheels, a brace 52 having rubber engaging feet 53 is placed under the upper end of the board 14. A chain 54 is connected between a cross bar 55 of the brace 52 and to the board by means of a snap hook in the manner shown in Fig. 5 and as indicated at 56 in Fig. 8. Detachable handles 57 in the board 14 serve as grips for the movement of the device over the floor.

To remove the patient from the device it is simply wheeled into the location alongside of the bed, wheels and handles are removed, and the board swung longitudinally of the bed so that the patient can be rolled from it.

While various changes may be made in the detail construction, it shall be understood that such changes shall be within the spirit and scope of

the present invention as defined by the appended claim.

Having thus set forth and disclosed the nature of my invention, what is claimed is:

5 An erecting and ambulating device for hospital and home use comprising a main board, a foot board hinged to the lower end of the main board and adjustable between a first position in alignment with the main board and a second position 10 in which the foot board extends at an angle to the main board, removable brace means for securing the foot board in the second position, wheel saddles, connecting means detachably securing said saddles to the under side of the 15 main board, said main board having openings for receiving said connecting means, and handle means for supporting and moving the device upon the wheel saddles, and said removable brace means comprising a tie rod, said rod having an enlargement on one end, said foot board having an opening in its edge, a U-shaped plate extending over the edge of the foot board and over the opening and itself having an opening therein with a slot, said opening receiving the 20 25 enlargement on the tie rod and said slot receiving the tie rod, a slide latch fitted under the U-shaped plate and extendable over the foot board opening to enclose the enlargement within the openings, said main board having a plate with a hole therein, said tie rod having a bent end fitted into the hole in the plate in the main board in a releasable manner and angled from the plate.
